(57) CLAIM

The ornamental design for cover panels for meter panels and air conditioner blow-off mouths of automobiles, as shown and described.

DESCRIPTION

FIG. 1 is a perspective view;

FIG. 2 is a front view;

FIG. 3 is a top plan view;

FIG. 4 is a bottom plan view;

FIG. 5 is a right side elevational view;

FIG. 6 is a left side elevational view; and,

FIG. 7 is a cross-sectional view taken along line 7—7 as shown in FIG. 2.
